(57) **CLAIM**

The ornamental design for a handle, as shown and described.

DESCRIPTION

FIG. 1 is an elevational view of a handle showing my new design;

FIG. 2 is a plan view thereof from the top of FIG. 1;

FIG. 3 is a side elevational view thereof from the right of FIG. 1;

FIG. 4 is a side elevational view thereof from the left of FIG. 1;

FIG. 5 is a plan view thereof from the bottom of FIG. 1;

FIG. 6 is an elevational view from the side opposite that

shown in FIG. 1; and,

FIG. 7 is a general perspective view of a handle showing my

new design.

The portion of the article shown in dotted lines forms no part

of the claim.
